EVERETT R. BURTNELL, OF SANTA ROSA, CALIFORNIA

INTERNAL-COMBUSTION ENGINE

Application filed April 11, 1929. Serial No. 354,286.

My invention relates to an internal combustion engine of the two stroke cycle principle and more particularly to a balanced horizontal opposed cylinder unit and has for its 5 principal objects the provision of an engine having a balanced system of moving parts forming the embodiment of a system of working parts with four combustion units arranged so as to develop two uniformly 10 spaced power impulses by each revolution of the crank shaft, to produce each of the two power impulses, coincident with a given revolution of the crank shaft by given events taking place synchronously within pairs of the 15 four combustion units, which are respectively oppositely disposed with respect to the axis of the crank shaft, and of the same transverse plane therewith to effect balanced torque forces, in an opposite direction, in the 20 respective transverse planes of the respective transversely opposed combustion units to effect the transmission of the power from pairs of synchronously actuated and oppositely moving pistons to the crank shaft in a manner 25 developing a balanced application of the torque forces to the crank shaft, without producing any radial thrust with respect to the free rotation axially by the shaft, by providing the engagement of the said pistons with 30 crank pins of the crank shaft that are diametrically oppositely disposed with the axis of the crank shaft and relatively located in a given transverse plane therewith.

Further objects of my invention are to provide an improved low cost, economical engine for light vehicle operation which will be of low gravity, inherently balanced, inherently easily cooled, embodying parts, which are as a whole, easily manufactured and 35 inherently of a design easily and cheaply assembled, being valveless thereby eliminating valve grinding adjusting and attention, long lived, rugged, simple, fool proof and silent of operation capable of providing greater 40 power from a given weight, cost of manufacture and operation with silence and perfect balance, which of a balanced unit lends itself to being produced and combined in multiplicities toward making up prime mover units 45 of great power.

Further objects of my invention are to provide a comparatively simple, low gravity balanced engine unit of low frontal area and made up of a system of moving parts, which are, by the specific combination and arrangement inherently in dynamic balance when in motion. 55

Further objects of my invention are to provide a valveless single crank shaft engine of opposed multicylinder construction which is particularly adapted to be operated of the two stroke cycle principle with either gasoline or Diesel, carburization or injection fuel systems, specifically of a system of reciprocal and rotary parts so combined and arranged, 60 that when in motion, all forces, inertia, centrifugal and torque, cancel out, without couple in close planes of opposed forces, making the use of counter balance weights unnecessary. 65

Further objects of my invention are to provide an eight cylinder two stroke cycle internal combustion engine balanced unit, having horizontally opposed cylinders and a low cost single plane crank pin crank shaft of a general design particularly adapted for aeronautical and automotive purposes and for other prime mover purposes whereof the essential requisite is dynamic balance of the system of moving parts and whereof great power from a given weight and engine cost is required. 70

By my improved construction, I have provided an engine in which the inertia forces, the centrifugal forces and the torque forces 75 will develop in a manner of respective planes which the respective forces, themselves of a kind, will be self counter balancing within approximately singular planes and in which all the forces at all times are transmitted to the crank shaft entirely along its axis, longitudinally with respect to the engine structure, of a balanced combination of opposed weight thereby permitting the crank shaft to 80 rotate freely within its journals without any appreciable radial load, and consequently therefore permit the crank shaft crank pins and main bearing sections being constructed 85 of comparatively small diameters, facilitating 90

great speed and acceleration without excessive centrifugal bearing loads.

The foregoing features of balance are of very great importance in the present day and as the demand increases for engines of greater power from a given weight, capable of operating continuously at greater speed, of a lesser number of parts, of less production and operating cost the foregoing features as disclosed as being the result of my present invention, will be found paramount and essential in the art of producing internal combustion prime movers.

With the foregoing and other objects in view, my invention consists in certain novel features of construction and arrangement of parts that will hereafter be more fully described and claimed and illustrated in the accompanying drawings, in which

20 Fig. 1 is a horizontal cross section taken transversely through the center of my improved engine;

Fig. 2 is a vertical horizontal section taken on line 2—2 of Fig. 1, the cutting line passing through two cylinders of opposed cylinder constructions, the ports of which are respectively adapted to admission of the scavenging charge;

Fig. 3 is a vertical longitudinal section taken on line 3—3 of Fig. 1;

Fig. 4 is a vertical longitudinal section taken on line 4—4 of Fig. 1;

Fig. 5 is a horizontal diagrammatic view of the pistons and crank shaft illustrating the direction of inertia forces with arrows located respectively in the various inertia force planes, by weights indicated by #2 representing to exist, when the bodies are in motion, in the respective piston stroke planes;

40 Fig. 6 is a horizontal diagrammatic view of the same form as Fig. 5 with the exception that the respective pistons are shown to be in the positions at the end of opposite stroke movements comparatively with the 45 piston positions as illustrated in Fig. 5;

Fig. 7 is a diagrammatic view of the cranks of the crank shaft illustrating the relative positions of the respective cranks of the shaft;

50 Fig. 8 is a horizontal diagrammatic view showing the two pairs of pistons respectively in pairs of cylinders relatively located on opposite sides and at opposite ends of the crank shaft and associated respectively with the 55 four cranks of the eight crank pin crank shaft which are co-axial and representing a longitudinally balanced half of the crank shaft;

Fig. 9 is a horizontal diagrammatic view, similar to Fig. 8 and showing the other two 30 pairs of pistons respectively in pairs of the other four of the eight cylinders which are respectively relatively located on opposite sides and at opposite ends of the crank shaft and associated respectively with the other 35 four of the eight crank pins of the shaft

which are co-axial and represent longitudinally the other balanced half of the crank shaft;

In Figures 5, 6, 8 and 9 the lines E—E indicate the rocking axis of the moving bodies of the engine longitudinally with respect to the rotary axis of the structure. 70

In Figures 5, 6, 8 and 9 the lines F—F indicate the rotary axis of the structure and may be taken as the longitudinal plane of the engine also. 75

Referring by numerals to the accompanying drawings which illustrate a practical embodiment of my invention, 10 designates a crank case within which a crank shaft 11 is rotatably journaled within three main bearings 12, 13 and 14. 80

This crank shaft is provided with eight cranks, the crank pins of which are designated by the numerals 15, 16, 17, 18, 19, 20, 21 and 22 respectively. Pins 15, 17, 20 and 22 are arranged co-axial and form one half of the balanced shaft while pins 16, 18, 19 and 21 are arranged co-axial and form the other half of the balanced shaft. The four 90

respectively co-axial pins 15, 17, 20 and 22 are relatively disposed diametrically opposite or 180° apart with the other four respectively co-axial pins 16, 18, 19 and 21 with respect to the axis of the crank shaft. Upon 95 examination it will be seen that each co-axial group of four crank pins respectively occupy balanced positions longitudinally from the center of the crank shaft, thus, when the shaft is in motion the entire rotary mass 100 will be in dynamic balance. The eight crank pins are formed in one plane which diametrically intersects the axis of the crank shaft and permits the eight pin shaft to be easily forged and cheaply and efficiently machined. 105

Fixed to and extending from the crank case 10 on two opposed sides in a horizontal plane therewith are two rows of cylinders, the two rows of cylinders are illustrated to be respectively formed as integral constructions 110 designated respectively by the numerals 31 and 32. Four cylinders are provided in each of the two rows, the four cylinders of the two rows embody an eight cylinder combination with the respective cylinders designated by the numerals 23, 24, 25, 26, 27, 28, 29 and 30. 115

A cylinder head member 33 is provided preferably detachable with the outer ends of each of the two rows of four cylinders. Two compression clearance chambers are provided 120 in each cylinder head member and respectively designated in each instance by the numeral 34, each compression clearance chamber provides a passage communication between the piston stroke sweep chambers of two parallel and adjacent cylinders and respectively form thereby dual cylinder combustion chambers of each adjacent parallel pair of cylinders arranged in a given one of the two rows. 125

Exhaust ports 35 are formed intermediate 130

the ends of one cylinder of each dual cylinder chamber and inlet ports 36 are formed intermediate the ends of the other cylinder of each dual cylinder chamber. The exhaust ports are preferably located in the end cylinders of each row to facilitate the provision of a direct outlet of comparatively large area and the inlet ports are preferably located in the center cylinders of each row to facilitate the provision of a Siamese inlet chamber 41 having a single supply duct communicating with the inlet ports of the two inlet port cylinders of each row of cylinders.

Eight pistons are provided, one piston arranged reciprocal within each of the eight cylinders. The eight pistons are respectively designated in simultaneous reciprocal pairs respectively arranged in a given row of cylinders in the manner as follows: A¹—A² of one dual cylinder chamber, B¹—B² of a second dual cylinder chamber, C¹—C² of a third dual cylinder chamber and D¹—D² of the fourth dual cylinder chamber, the A and B pistons being arranged on one side of the crank shaft and the C and D pistons being arranged on the opposite side of the crank shaft.

Eight connecting rods are provided, one rod connecting one of the eight pistons respectively with one of the eight crank pins of the crank shaft, the rods are designated by the numeral 39.

An ignition device 40 is provided with each clearance chamber of each dual cylinder chamber.

An inlet passage duct 43 is formed in each cylinder block and similar inlet passage ducts 49 and 50 are formed in the two sides of the upper part of the crank case. The passage ducts 49 and 50 of the crank case communicate respectively on each side with the passage duct 43 of the coinciding cylinder block, the duct 43 of each cylinder block is formed to communicate with the inlet passage chamber 41 in communication with the inlet ports of both inlet port cylinders of the respective cylinder block and the ducts 49 and 50 of the crank case terminate at a common port 48 to which a compressor illustrated and designated by the numeral 52 having a discharge port 54 may be attached.

An inlet port to the compressor chamber is designated by the numeral 53, a carburetor 55, for illustration, may be connected with the compressor by means of an elbow fitting 56. A driving gear between the compressor parts and the crank shaft of the engine is designated by the numeral 60.

On the upper and lower sides of each cylinder block the inlet passage chamber 41 is preferably open for its entire length through the side walls of the respective blocks facilitating examining and cleaning of the ports of the centrally located cylinders, these passages 41 are closed on the upper side by plates

42 and on the under side by plates 51, the lower plates 51 are provided on their inner sides with a drain groove 57 which preferably inverts to the center, which point is directly beneath the point where the inlet supply duct 43 of each block communicates with the passage chamber 41 and directly between the two central cylinders which are spaced apart sufficiently to permit the liquid particles, usually termed as heavy ends of the fuel mixture, to drop between the respective cylinders directly into the drain 57, facilitating the flow of only the dry well vaporized fuel mixture reaching the inlet ports of the adjacent cylinders.

Drain pipes 46 are provided respectively in communication with the drain 57 of each under plate 51 of each block and join with a main drain pipe 47 which extends to a point communicating with the induction side of the compressor whereof the vacuum will effect the withdrawal of the undesired fluid residual from the inlet passages of each cylinder block preventing pooling of the fuel liquid and uneven operation of the engine under variable conditions.

The crank case may be made barrel type with center and end main bearings constructed removable within retainer bushings if desired and the rods may be assembled with the crank shaft by admission of the operator through the lower side of the crank case to which an oil pan 61 of ample size may be secured.

A fluid outlet 44 is preferably located directly over each cylinder at a point near the crankwardly extending base of each common cooling fluid cell of the respective cylinder block and a fluid inlet port 45 is preferably located on the underside directly under the ignition device at the headward end of each cylinder. The location of the cooling fluid inlet and outlet ports with respect to each combustion unit is detailed to assume improved cooling of the cylinder head walls and particularly the parts immediately surrounding the ignition device, the admission of the cooling fluid at first to the head end of the cylinders and on the under side thereof assuring the fluid first engaging the area of the combustion chamber walls, which is subjected to the highest temperature, and also the circulation of the water from the under side upward around the chambers will effect a circulation of all the cooling fluid in the natural direction of thermal flow and thereby greatly removes the possibility of steam traps adjacent the hot walls of the combustion chambers so detrimental to normal combustion and smooth operation of an internal combustion engine.

Practically all of the features set forth in my present application as being accomplished by my present invention are of far greater importance in the operation of an internal

combustion engine of the two stroke cycle principal than of the four stroke cycle principal and subsequently therefor the objects of my present invention are of considerably greater significance than would commonly be understood.

I wish to further point out that a very great advantage in the construction of a compressor induction two stroke cycle engine in accordance with my improved horizontal cylinder engine will particularly be found to reside in the inverted form of fuel mixture passage ducts from the carburetor to the combustion cylinders, which the opposed horizontal arrangement of cylinders and ducts constructed in the crank case provides without greatly increasing the height of the compressor relatively with respect to the axis of the crank shaft and the mean center of gravity of the engine structure.

The operation of my improved engine is accomplished in the conventional two stroke cycle scavenging manner, a compressor being depended upon for forced induction of scavenging air or gaseous mixture, as the case may be, the pistons within the respective dual parallel cylinder combustion chambers being adapted to control the admission and exhaust ports respectively of the two cylinders of each chamber.

Obviously the development of dual synchronously timed power impulses in opposed units is accomplished by the specific arrangement of the pins of the shaft and the relative association of the opposed pistons with the respective pins. It will be seen that in my improved construction, the opposed pistons of a given pair of commonly connected opposed cylinders, occupying a given transverse plane with the crank shaft at one end of the structure, are connected to the respective end crank pins which are on dead centers on the near side to the respective cylinders of which the respective pistons therein are connected and that the opposed pistons of the other pair of commonly connected opposed cylinders respectively occupying another given transverse plane with the crank shaft, at the other end of the structure, are connected to the respective end crank pins, of the other end of the shaft, which are relatively rotatively of positions on dead centers furthermost from the respective cylinders of which the respective pistons therein are connected.

Obviously this combination and relationship of reciprocating and rotary parts provides two dual synchronously timed opposed power impulses to the crank shaft by each revolution of the shaft, the two opposed power impulses being relatively developed 180° , apart with respect to the rotation of the crank shaft and the combination and arrangement of parts, forming the embodiment of my improved engine, further accomplishes

the development of only opposed forces of any nature, in a given plane of respective forces and completely throughout the entire system of moving bodies, leaving the crank shaft freely rotatable in the main bearings with only the shaft weight friction as a mechanical consideration between the crank shaft and the journal bearings thereto.

In my improved construction each power impulse is transmitted to the crank shaft through four big end bearings of four rods to four respectively separated crank pins of exactly opposed weight and synchronously transmitting the same force of exactly opposed angularity of thrust, obviously therefor, the torque is produced rotatably of the crank shaft from four pistons simultaneously and directly to four points of the shaft and distributed over exactly one half of the crank shaft. This latter feature being of great importance to mechanical perfection in an engine, almost equally so, for either extremes of the field, namely small high speed supercharged or nonsupercharged engines or very large industrial units whereof the unit forces are tremendous.

With reference to the Figures 5, 6, 8 and 9, of the accompanying drawings, a study of the Figures 5 and 6 will illustrate the perfect balance of the inertia forces in any position, in Figure 5 it will be seen that pistons A^1 and A^2 representing the synchronously actuated reciprocating members of a given end pair of cylinders of the first side are at head end center and their respective inertia forces are represented as being respectively of $2\#$ outward from the axis of the crank shaft in the stroke plane of each respective piston, at the same moment pistons D^1 and D^2 of a pair of opposed cylinders of the other side and designated as the second side and located at the opposite end of the structure, are in the position of crank end center and their respective inertia forces are represented as being also respectively of $2\#$ outward from the axis of the crank shaft, but from the opposite side, therefore the inertia forces of pistons A^1 and A^2 and relatively longitudinally stepped and opposed pistons D^1 and D^2 are of the same transverse direction collectively toward the said first side and since the four respective endwise crank pins are co-axial and longitudinally balanced, the combined inertia forces of the four respective pistons, of offset opposed cylinders, of opposite ends of the opposed rows of cylinders, produce a uniform weight in a given direction and toward the said first side away from the axis of the crank shaft.

With further reference to Figure 5 it will be seen that pistons B^1 and B^2 , of cylinders located at the other end of the said first side, are in the position of crank end dead center and their inertia forces are respectively represented as being $2\#$ respectively

in each stroke plane of the respective pistons and in the direction of the said second side and at the same moment the position of pistons C¹ and C² of the fourth pair of cylinders, respectively located on the said second side and at the opposite end relatively with the cylinders of the first side containing pistons B¹ and B², are of head end dead center, and being of cylinders of the 10 said second side, the inertia forces of the respective pistons are likewise represented as respectively of 2# and of an outward direction from the axis of the crank shaft toward the said second side.

15 It will be seen that the four pistons B¹ and B² and C¹ and C² are connected to four co-axial cranks which are of relatively longitudinally balanced positions and relatively diametrically opposite the other four co-axial 20 cranks to which the pistons A¹, A², D¹ and D² are connected, therefore the inertia forces of pistons B¹, B², C¹ and C² are of the same transverse direction collectively toward the 25 said second side and since the four respective endwise crank pins, to which the said pistons are connected, are co-axial and longitudinally balanced the combined inertia forces of the said four pistons B¹, B², C¹ and C² produce a uniform weight in a given direction 30 along the axis of the shaft toward the said second side, thus the combined forces of the pistons A¹, A², D¹ and D² in an outwardly direction from the axis of the crank shaft toward the said first side are equal and perfectly 35 cancel out, without the slightest rocking couple, the combined inertia forces of the pistons B¹, B², C¹ and C² of which the forces are collectively produced in an outward direction from the axis of the crank shaft toward the 40 said second side.

Figure 6 illustrates the relative position and direction of inertia forces of the pistons when the pistons are respectively at opposite end centers from that shown in Figure 3 and 45 as caused by one half revolution of the crank shaft from the shaft position as shown in Figure 5.

With reference to Figures 8 and 9 of the accompanying drawings, Figure 8 illustrates 50 the two pairs of offset and oppositely disposed pistons and their connections with one co-axial group of four crank pins, the arrows indicating the direction of the inertia force of the respective pistons showing the forces 55 to be collectively in common toward the said first side, Figure 9 illustrates the other two pairs of relatively offset and oppositely disposed pistons and their connections with the other or second relatively co-axial group of 60 four crank pins of the crank shaft, which second group of crank pins are relatively rotatively disposed 180° apart with the said first group of four relatively co-axial crank pins, the arrows indicating the direction of 65 the inertia force of the respective pistons

showing the forces to be collectively in common toward the said second side, directly counter to the forces of the other four pistons as illustrated in Figure 8.

It is to be understood that a multiplicity of my improved balanced engine units respectively of eight cylinders and eight crank pin crank shaft may be constructed in one integral structure if desired and that the section of the crank shaft adapted to one eight cylinder unit may be relatively disposed with another section of crank shaft, respectively related to another unit of eight cylinders, rotatively of a crank pin position respectively providing a differential of pin positions rotatively with respect to the pin positions rotatively of another given section of shaft adapted to another given unit of cylinders to produce a greater frequency of power impulses by one revolution of the crank shaft.

It will be further understood that my invention as to its broader aspects is not limited to the precise construction herein set forth, as many changes may be made therein without departing from the spirit of my invention and without sacrificing its chief advantages.

I claim as my invention:

1. In an internal combustion engine, two rows of four cylinders each arranged to form a horizontal opposed structure, the eight cylinders being arranged in four pairs with the head ends of the members of each pair connected by a common compression and combustion clearance chamber, one cylinder of each four pairs having exhaust ports and the other cylinder of each four pairs having inlet ports, eight pistons, one piston arranged for reciprocatory movement within each of the eight cylinders, a crank shaft having eight crank pins disposed in two co-axial groups of four crank pins each, the eight crank pins being formed in one plane, two pistons of each of the two opposed rows of cylinders being connected respectively of opposed rows of cylinders to two adjacent crank pins of one co-axial group and an ignition device provided with each common compression chamber.

2. In an engine, eight cylinders arranged in two rows of four cylinders each, the chambers of the first and second cylinders from each end of each of the two rows being connected at their head ends by a common compression clearance chamber, pistons arranged for operation within all the cylinders, the two rows of cylinders being arranged with axes parallel and axially disposed in a common parallel plane, a crank shaft having eight throws with crank pins thereof relatively disposed rotatively in two co-axial groups of four crank pins each, the first and third crank pins from each end of the shaft being co-axial, the second and fourth crank pins from each end of the shaft being co-axial,

the respective crank pins of the two co-axial groups being alternately disposed with respect to their longitudinal order relatively diametrically opposite with respect to the axis of the crank shaft, the crank shaft being disposed between the two rows of cylinders, the pistons of the first and second cylinders respectively from a given end and relatively of opposite ends transversely of the two opposed rows of cylinders being connected respectively of pairs of adjacent commonly connected cylinders respectively to the first and second relatively co-axial crank pins of the crank shaft which are coincident with the respective endwise location of the respective cylinders and are respectively crank pins of a given one of the two groups of four relatively co-axially disposed crank pins and which are respectively spaced longitudinally by the respective crank pins of the other of the two groups of four co-axial crank pins and relatively of diametrically opposite positions.

3. In an engine, a balanced structure of units, comprising in combination four commonly connected pairs of relatively axially parallel cylinders, the four pairs of cylinders being arranged in two rows of two commonly connected pairs of cylinders each, the cylinders of the two rows being relatively axially disposed in a common plane and spaced apart sufficiently to permit the installation of a crank shaft between the two rows of cylinders, a crank shaft having eight crank throws disposed between the said two rows of cylinders, the cylinders of the two rows being respectively disposed coincident in the planes of the eight crank throws of the crank shaft and alternately of rows respectively coincident with every other crank throw thereof, the eight crank pins of the eight crank throws being disposed in two co-axial groups of four crank pins each, the first and third crank pins respectively from each end of the crank shaft being co-axial and comprising one of the said two co-axial groups of four crank pins, the second and fourth crank pins respectively from each end of the crank shaft being relatively co-axial and comprising the other of the said two co-axial groups of four crank pins, the two co-axial groups of crank pins being relatively diametrically oppositely disposed 180° apart, eight pistons, one piston arranged reciprocal within each cylinder, the four pistons of each row of cylinders being connected in pairs respectively of commonly connected cylinders of each row with adjacent co-axial pairs of crank pins of both of the two diametrically oppositely groups of co-axial crank pins.

4. In an engine the combination of eight cylinders, eight pistons, a crank shaft having eight crank pins and connections between the said eight pistons singularly with the

eight crank pins thereof, the disposition of the eight cylinders in two rows each comprising four opposed cylinders to the other row, the crank shaft being interposed between the two rows of cylinders, all the cylinders being axially parallel, the eight crank pins being relatively disposed in two groups of four crank pins each, the four crank pins respectively of each of the two groups being relatively disposed axially in line and axially parallel with the axis of the crank shaft, the two groups of axially aligned crank pins being relatively rotatively spaced 180° apart, every other crank pin from a given end of the crank shaft being formed in a given one of the two axially aligned crank pin groups and the pistons of the first and second cylinders relatively of opposite ends of each of the two opposed rows being respectively connected to the respective endwise two of the four axially aligned crank pins of a given axially aligned group of crank pins of the crank shaft.

5. In an engine, eight cylinders, eight pistons, one piston arranged for reciprocatory movement within each of the eight cylinders, a crank shaft, eight crank throws formed of the crank shaft, a crank pin formed of each of the eight crank throws of the shaft, the eight crank pins being disposed in two co-axial planes of four co-axial crank pins each, the four crank pins disposed in one common axial plane being relatively rotatively disposed 180° apart with the other four crank pins relatively disposed in the other of the two common axial planes, the four crank pins comprising either of the two co-axial groups respectively of a common axial plane being separated and spaced longitudinally and alternately by the respective pins of the other four relatively co-axial crank pins comprising the other of the two co-axial groups of pins respectively of another common axial plane, the pistons of the first and second cylinders of each of the two opposed rows and respectively diversely located at opposite ends of the rows thereof being connected respectively in pairs of relatively adjacent cylinders to the first and second relatively co-axially disposed crank pins of the shaft from the respective end of the shaft which is coincident with the respective cylinders.

6. In a two stroke cycle internal combustion engine, the combination with eight cylinders equally arranged in opposed formation of a system of moving bodies, comprising a crank shaft having eight crank pins, the first, third, sixth and eighth crank pins from either end of the shaft being formed of a common axis, the second, fourth, fifth and seventh crank pins from either end of the shaft being formed of a common axis, the first, third, sixth and eighth crank pins from either end of the shaft and of co-axial alignment being axially relatively rotatively

disposed 180° apart with the axes of the said third, fourth, fifth and seventh crank pins from either end of the shaft and respectively being of co-axial alignment, eight pistons, 5 one piston arranged for reciprocatory movement in each of the said eight cylinders, the four pistons of the cylinders of one side of the said opposed cylinder formation being respectively connected with the first, third, fifth and seventh 10 crank pins from a given end of the shaft and the four pistons of the cylinders of the other side of the said opposed cylinder formation being respectively connected with the first, third, fifth and seventh 15 crank pins from the other end of the crank shaft.

7. In an eight cylinder horizontal opposed internal combustion engine, the combination of a balanced system of moving bodies comprising, a crank shaft having eight crank 20 throws, a crank pin formed of each crank throw, the eight crank pins being arranged in two co-axial groups of four crank pins each, each adjacent pair of crank pins being 25 relatively disposed 180° apart, every other crank pin being axially disposed coincident with three other crank pins, eight pistons, four pistons disposed on one side of the crank shaft and arranged reciprocal respectively 30 within cylinders comprising one of the two opposed groups, the four other pistons being disposed on the diametrically opposite side of the crank shaft and arranged reciprocal within other cylinders which comprise the 35 other of the two opposed groups and the four pistons of either of the two opposed groups of cylinders being respectively separately connected to every other one of the crank pins of the crank shaft.

40 8. The combination in a two stroke cycle internal combustion engine, of eight cylinders, eight pistons, one piston arranged for reciprocatory movement within each of the eight cylinders, a crank shaft having eight 45 crank throws formed in a single plane, a crank pin formed of each of the eight crank throws, the eight cylinders being arranged in two rows of four cylinders each on two relatively diametrically opposite sides of the 50 crank shaft, each row of cylinders being coincident with the axis of the crank shaft, the eight cylinders being disposed with axes parallel, the four cylinders of each side being formed in pairs, the chambers of the members 55 of each pair being connected at their head ends by a common compression clearance chamber, the first, third, sixth and eighth crank pins from either end of the shaft being co-axial, the second, fourth, fifth and seventh 60 crank pins from either end of the crank shaft being co-axial, the said first, third, sixth and eighth crank pins being disposed relatively rotatively 180° apart with the said second, fourth, fifth and seventh crank pins, the four 65 pistons on one side of the crank shaft being

connected to the first, third, fifth and seventh crank pins from one end of the crank shaft, the other four pistons respectively disposed on the other side of the crank shaft being connected to the first, third, fifth and seventh 70 crank pins from the other end of the crank shaft, exhaust ports formed in one cylinder and inlet ports formed in the other cylinder of each commonly connected pair of cylinders and ignition means provided in the head of each pair of connected cylinders. 75

In testimony whereof I affix my signature.
